Primary Examiner — Mehri F Bajoul(74) *Attorney, Agent, or Firm* — Nitin Kaushik(57) **CLAIM**

The ornamental design for stacking cups, as shown and described.

DESCRIPTION

FIG. 1 is a perspective view of stacking cups showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the portion designated as 8 in FIG. 7.

The broken lines in the drawings depict portions of the stacking cups that form no part of the claimed design.
